UNITED STATES PATENT OFFICE

WALTER M. GLEASON, OF OAKLAND, CALIFORNIA

COIN-CONTROLLED LOCK

Application filed November 30, 1926. Serial No. 151,696.

My invention relates to a lock arranged to be rendered operative by and upon the insertion of a coin, or the like, therein, and of a class wherein the coin itself is utilized as an essential mechanical element in a primary operation of the lock.

An object of the invention is to provide a lock of the class described, whereby the insertion of a coin in the coin inlet slot directly effects the fixed setting of a closure means for the slot before the coin assumes its operative relation to the lock.

Another object of the invention is to provide an improved and particularly simple means for controlling the positioning of the closure means for the coin receiving slot.

The invention possesses other objects and features of advantage, some of which, with the foregoing, will be set forth in the following description of the preferred form of my invention which is illustrated in the drawings accompanying and forming part of the specification. It is to be understood, however, that I do not limit myself to the showing made by the said drawings and description, as I may adopt variations of the preferred form within the scope of my invention as set forth in the claims.

Referring to said drawings,

Figure 1 is a side sectional view of a lock embodying the invention, with the bolt thereof operatively disposed.

Figure 2 is a side view of the lock with the bolt in withdrawn position, portions thereof being broken away to disclose the relation of the operative parts.

Figure 3 is a view of the lock taken on the line 3—3 of Figure 1, and mounted on a door.

Figure 4 is an edge view of the lock mounted on a door.

Figure 5 is a sectional view taken on the line 5—5 in Figure 2.

As herewith particularly illustrated, the lock 7 of my invention comprises a movable latch plate 8 arranged to effect the operation of a latch-bolt 9 and to be independently operated from opposite sides of the lock by and upon the appropriate manual actuation of mutually independent means such as the spindles 11 and 12 shown. The lock mem-

bers are here shown mounted on a plate 13, which plate is arranged to be secured directly to a door 14 and serves as part of the lock casing. As here shown, the latch plate 8 is vertically slotted at the inner end thereof to provide an opening 16 therethrough of less width than the diameter of a discate member which is designed to be used in rendering the lock operative from the outside of the door, a coin 17 being here shown so utilized. Parallel and generally vertical opposed grooves 18 are provided in the slot side walls 19, such grooves cooperating to provide a passage whereby a coin may move into and through the slot in transverse relation thereto.

Extending from the plate 13 at the top and sides thereof are spacing members, or posts, 21 and 22 respectively, such members being arranged to have a plate 23 demountably secured thereto by means of screws 24. The plates 13 and 23 are preferably parallelly disposed and are so spaced that the latch plate 8 slidably engages between them. Fixed on each of the plates 13 and 23 are upper and lower guide members 26 and 27 respectively, such members being disposed generally horizontally so that the latch plate is guided for horizontal reciprocative movement. Fixed to the spindle 11 is an arm 28 which extends radially of the spindle axis and has its outer end 29 disposed in the latch plate opening 16. It will now be noted that when no coin is disposed in and between the latch plate grooves 18, the arm 28 may be oscillated between a position against the forward wall 30 of the opening 16 of the latch plate and a stop 31, the latter being here shown provided on one of the lower guide members 27. By means of a spring 32 operatively disposed between the arm and a post 22, the arm is resiliently urged to maintain the forward position in the opening 16, in which position its end 29 is disposed forwardly of the grooves 18. When, however, a coin is disposed in the grooves 18, the retractive rotation of the arm will cause the end 29 thereof to engage the coin so that a continuation of such rotation will retract the latch plate and so withdraw the bolt 9 from its extended position,

the coin thus becoming an operative part of the lock for the bolt withdrawing operation.

Means are provided for assuring the operative positioning of the coin in the latch plate during the withdrawal of the latter and for releasing the coin at the completion of such action. Accordingly, and as here shown, at least one of the lower guide members 27 is provided with an inwardly extending portion 33 which is arranged to slidably contact with the lower edge portion of the coin prior to and during the retractive movement of latch plate, and terminating at such a place that the coin is permitted to fall through and from the grooves substantially at the completion of such movement and when the rotative effort is discontinued by the operator. In this manner, the coin is arranged to drop from the latch plate upon complete withdrawal of the bolt, while a partial withdrawal which will not effect an unlocking of the door does not release the coin.

It will now be noted that when the latch plate is in forward position, the coin passage 18 through the latch plate defined by the grooves 18 is disposed in coplanar relation with the axis of spindle 11, and that when the latch plate is so positioned, a coin is arranged to be inserted therein from above. Fixed to the plate 13 is a member 34 having extending vertically therethrough a coin passage 36 which registers with the coin passage of the latch plate when the latter is in forward position, it being noted that should a coin be inserted in the passage 36 when the latch plate is out of such position, its downward movement into an operative relation with the latch plate would be prevented by means of its engagement with the top edges of the slot side walls 19. In this manner, the passage of a coin through the latch plate in any other manner than one to render the lock operative is positively prevented.

Mounted on the spindle 12 is a member 37 having an arm 38, the extremity of which arm is arranged to maintain a position in the latch plate opening 16 forwardly of the rear wall 39 of such opening whereby appropriate rotation thereof will effect a withdrawal of the latch plate independently of the operative turning of the spindle 12. A spring 41 is preferably operatively disposed between the arm 38 and the plate 13 whereby the arm may be held in forward position when the latch plate is retracted by means of the arm 28. It will be noted that by reason of the engagement of the arm 28 with the wall 30 of the latch plate, the spring 32 also functions to resiliently resist withdrawal of the latch plate by means of the arm 38. It will now be clear that the independent operation of the lock by means of the appropriate rotation of either of the spindles 11 and 12 is provided for, but that the former requires the use of a coin, whereas the latter is operable at all

times; accordingly, since the lock is particularly designed for use where ingress through a door requires the deposit of a coin and free egress is to be permitted, the spindle 11 is here shown arranged to be operated from the outer side of the door as by a knob 42, while the spindle 12 is arranged to be operated from the inner side of the door by a knob 43. To permit the opening of the door from the outside by an attendant, the spindle 12 may also be arranged, as here shown, to be actuated from the outside of the door by a suitable key (not shown).

It will now be noted that one of the chief uses of the lock would be on the doors of pay

80

toilet rooms, and that when the room is occupied it is highly desirable that the entrance of a second person thereto from the outside be prevented.

Means associated with the lock are accordingly provided, and as here shown, such means comprises the provision of a device for preventing the insertion of a coin in the lock until the lock has been operated by means of the spindle 12 to permit the exit of the first person.

85

Mounted on the member 34 at a side thereof for free pivotal movement about a pivot pin 44 in a plane parallel to the plate 13 is a generally crescent-shaped member 46 pivoted intermediate its ends so that it may be pivotally moved between extreme positions to have one

90

end or the other lie across an end of the passage 36 to provide an obstruction to the passing of a coin therethrough. Normally, the lower end 47 is disposed across the passage

95

36 adjacent the bottom while the upper end 48 is disposed adjacent the top of the passage but not across it. When a coin passes downwardly through the passage, it displaces the end 47 of the member 46 from its position

100

across the passage and thereby, through the pivotal movement of the member, interposes the upper end 48 across the passage to thereby close the passage to the insertion of a coin

105

from above. Since the movement of the coin out of the passage 36 into the latch plate terminates its contact with the member 46, means are provided for positively and

110

reliably holding the member 46 operative to maintain its closure of the passage until the insertion of another coin is desirable.

115

The holding means for the member 46, it will be noted, is preferably arranged to be rendered inoperative upon the rotation of the spindle 12 to open the door to effect an exit, and may be of any suitable nature. As here shown, I employ a magnet as an operative part of one means for insuring a continued closing of the passage 36 against the insertion of a coin while such is desirable.

120

Adjustably positioned in the plane of movement of the member 46 is a magnet 51, here shown of horse-shoe form, having the poles 52 thereof disposed to provide a stop for the upper end 47 of the member 46, such end providing an

125

130

armature 53 for the magnet, so that the member 46 will be magnetically held to the poles 52 upon being moved thereagainst by the movement of a coin through the passage; as here shown, the magnet is adjustably secured to the member 34 by means of a clamp bar 54 and screw 56, the lower end of the bar 54 being utilized as the stop for the end 47 of the member 46. The member 46 is preferably formed of a light non-magnetic substance such as aluminum, with the armature 53 fixed on the forward face of the end 48 thereof, it being noted that the member, when so formed, is most readily displaceable by a coin and, because of its resistance to corrosion, maintains its freedom of movement about the pivot. Furthermore, to further assure the maintenance of the member 46 in either of its extreme positions, the mounting of the member 46, both in terms of its shape and the distribution of its weight, is preferably such that at an intermediate position it will be supported on its pivot in a condition of neutral equilibrium, whereby it will tend to stay in either of such extreme positions. In this manner, the displacement of the member 46 from its passage closing position must be positively accomplished, preferably, as has been hereinbefore indicated, by and upon movement of the spindle 12. Accordingly, an extension 57 is here shown provided on the member 37, which extension, upon the opening rotation of the spindle, is arranged to engage the back edge 58 of the member 46 when such member is on the magnet side of its position of neutral equilibrium, whereby the engagement of the armature 53 with the magnet may be broken and the member 46 may be restored to its normal position to permit the insertion of a coin in the passage 36. In this manner, by the use of magnetic means, a positive and simple means for holding the member 46 operatively disposed is provided.

Means are provided for recording the number of coins which pass through the lock mechanism, and as here shown such means comprises the provision of a recording device 61 of suitable structure having a trip arm 62 thereof interposed in the path of the coins as they fall from the latch plate, following their release from operative position therein. To guide the coins against the trip, opposed slots 63 and 64 are provided in the plates 13 and 23 respectively, the inlets of such slots being disposed at the inner ends of the portions 33 of the guide members 27. In this manner, the coin itself causes a record to be made by means of its fall into the lower portion of the housing and without involving any operation of a recording device in connection with the inlet passage or with the latch-plate of the lock, so that the possibility of interference of the recording device with the operation of the lock mechanism is reduced to a minimum.

I claim:

1. In a door-lock, a member providing an inlet slot for a coin, closure means for the slot arranged to be set in operative position solely by and upon the passage of a coin through said slot, and means independent of

- the coin to releasably hold the closure means in operative position.
2. In a door-lock, a member providing an inlet slot for the admission of a coin to the lock from one side thereof, closure means for the slot arranged to be set in operative position solely by and upon the passage of a coin completely through said slot, means independent of the coin to releasably hold the closure means in operative position, and means operative from the other side of the lock to effect release of said closure means.
3. In a door-lock, a member providing an inlet slot for a coin, and a normally inoperative pivotally mounted closure member for the slot arranged to be fixedly held in its operative position independently of said coin by and upon the passage of the coin through said slot with said closure member obstructing the intake end of the slot, said member being arranged to be in neutral equilibrium with respect to its pivotal axis when disposed intermediate its operative and inoperative positions whereby it will tend to maintain its position when disposed in either of said positions, and means independent of the coin for releasably holding the closure member in position to prevent insertion of a coin into said slot.
4. In a coin-controlled door-lock, a member providing an inlet slot for a coin, a normally inoperative closure means for the slot arranged to be set in operative position to prevent full insertion of an object into said slot by a coin passing completely through the slot, and means including a magnet operative to hold the closure means in said set position following the movement of the coin from the slot.
5. In a coin-controlled door-lock, a member providing an inlet slot for a coin, normally inoperative closure means for the slot, means interposed in the path of a coin in the slot displaceable by the coin to operatively dispose said closure means into position to prevent insertion of an object through the intake end of the slot, and means thereafter operative independently of said coin to releasably hold said closure means in operative position.
6. In a coin-controlled door-lock, means defining an inlet passage for a coin, a member mounted for movement to and between a pair of limiting positions and arranged when in each of said positions to have a different portion thereof interposed in said passage, one of said portions when disposed in said passage being displaceable by a coin to move said member to the other of said limiting positions to dispose the other of said portions in said passage whereby a closure is provided for the intake end of said passage to prevent the insertion of a second coin therein, and means independent of said coin operative to hold said member in position to provide a closure for the intake end of said passage.
7. In a coin-controlled lock, means providing an inlet passage for a coin, a normally inoperative pivotally mounted closure member for the passage arranged to be operatively disposed by and upon the passage of a coin completely through the passage, said member being arranged to be in neutral equilibrium with respect to its pivotal axis only when disposed intermediate its operative and inoperative positions, and magnetic means operable to hold said closure member operatively disposed.
- In testimony whereof, I have hereunto set my hand at Oakland, California, this 10 day of November, 1926.
